ANTIFOG HEADLIGHT FOR VEHICLES

Francesco Cassinelli, Venegono Superiore, Italy, assignor
to Messrs. Fratelli Pagani, Milan, Italy, an Italian firm

Application June 1, 1956, Serial No. 41,729

Term of patent 3½ years

(Cl. D48—32)

Fig. 1

Fig. 4

Fig. 2

Fig. 3

Fig. 1 is a front elevational view of an antifog headlight for vehicles showing my new design;

Fig. 2 is a side elevation thereof;

Fig. 3 is a top plan view thereof; and

Fig. 4 is a transverse vertical section of the lens.

I claim:

The ornamental design for an antifog headlight for vehicles, substantially as shown.
